UNITED STATES PATENT OFFICE.

JAMES ROBERT ADAMS, OF KENOSHA, WISCONSIN.

COOKING APPARATUS.

No. 853,147.

Specification of Letters Patent.

Patented May 7, 1907.

Application filed June 28, 1906. Serial No. 323,795.

To all whom it may concern:

Be it known that I, JAMES ROBERT ADAMS, a subject of the King of Great Britain, and a resident of Kenosha, in the county of Kenosha and State of Wisconsin, have invented a new and Improved Cooking Apparatus, of which the following is a full, clear, and exact description.

This invention relates to certain improvements in containers having thick insulated walls, and adapted to receive vessels of partially cooked food, which after having been brought to the boiling point or cooked for a short length of time in any suitable manner are tightly sealed and inclosed within the insulated walls. The heat retained in the vessel of partially cooked food is thus prevented from being dissipated and the food continues to cook for a considerable length of time. By sealing the cooking vessel before inserting it in my improved heat retaining device, the steam is prevented from escaping to moisten, warp or soil the device, and at the same time the cooking action is very materially prolonged.

Reference is to be had to the accompanying drawings which form part of this specification, in which drawings similar characters of reference indicate corresponding parts in the several views, and in which

Figure 1 is a perspective view of the cooking apparatus having the cover thereof open; and Fig. 2 is a vertical section on the line 2—2 of Fig. 1.

According to the form of the invention here shown, my improved cooking apparatus consists of a box 1 preferably of wood, although other suitable non-conducting material, as papier-mâché for instance, may be used. This box is provided with a hinged cover 2, and both the box and cover are lined with corrugated or fluted paper 3. The cover 2 has a lining 5 of fabric which is secured to the walls of the cover by a wooden frame 6. Between this fabric and the corrugated paper is interposed a packing of glass wool or other suitable insulating material 4. In constructing the cover it has been found most advantageous to secure the fabric 5 by means of the frame 6 and then insert the packing 4 and corrugated paper 3 through the top of the cover in order that the fabric may be securely held in place and no free edges exposed.

The box 1 is provided with a sheet metal lining having a flat upper surface 8 flush with the top of the box. This lining is secured in

place by a downwardly extending flange 9 which may be riveted or otherwise suitably fastened to the walls of the box. From the flat surface 8 of this lining depend a plurality of wells or nests, each having walls 10 parallel to the walls of the box, and a bottom 11 parallel to the bottom of the box. The bottom 11 is soldered or riveted to the wall, and the walls are similarly secured to the surface 8 so that the same is air tight and water tight. Between the wells and the walls of the box are interposed a layer of corrugated paper and a packing of glass wool or other suitable insulating material similar to the construction employed in the cover.

In connection with the heat insulating container above described, I use cooking vessels 12 preferably of granite or enameled ware which are each provided with compression or friction lids adapted to seal the same air tight, and retain the steam and the flavor of the food. These cooking vessels are suspended and spaced from the walls of the nests by flat handles 14 secured to the vessels near the tops thereof and resting upon the upper surface 8 of the metallic lining. The covers 13 of the cooking vessels are provided with rings 15 which form handles to facilitate the removal of the covers, and also constitute means whereby the cover may be hung up when not in use.

In the use of my improved device above described, the vessels 12 are heated in any suitable manner until the food is partially cooked. They are then inserted in the wells, as clearly shown in Fig. 2, and the cover 4 is closed and fastened by means of catches 7. The heat retained in the sealed vessel 12 is kept from being dissipated and the cooking action will continue for a very considerable length of time without the use of any additional fuel, thus effecting a very material saving. Between the vessel 12 and the outside atmosphere there is first the air space between the vessel and the well, then the insulating material 4, the corrugated paper 3, and lastly the wooden box 1, which thus form an almost perfect non-conductor of heat. Between the wells and the outer walls of the box there are no braces, posts or supports to conduct away the heat, and all the surfaces of the box are smooth and easily cleaned so that the box may be very readily kept in a sanitary condition, free from dust, dirt and particles of food.

It is very evident that my improved device

may also be used to keep articles at a low temperature as well as at a high one, for if ice cream or any other substance which it is desired to keep in a cold or frozen condition be placed in the receptacle 12, the insulating walls of the device would prevent the transmission of heat to the inside as efficiently as does it prevent the dissipation of heat from the inside when the device is used as a cooking apparatus.

Having thus described the preferred form of my invention I claim as new and desire to secure by Letters Patent:—

1. An insulating receptacle, comprising a container, a rigid lining secured therein and having the top portion thereof substantially parallel with the top of the container and having a well depending from said top portion, the walls of said well being spaced from the walls of the container, an insulating material between the walls of said container and the well, an air-tight vessel suspended within said well and spaced from the walls thereof, said vessel having flat rigid handles extending outwardly from each side thereof and adapted to rest upon the top portion of the lining and support said vessel out of contact with the well, and a cover for said container having a lining secured to the walls of the cover and a packing of insulating material between the top of said cover and said

lining, the lining adapted to contact with the top portion of the lining to the container and hold the flat handles of the vessel in place.

2. An insulating receptacle, comprising a container of non-conducting material, a rigid lining having the top portion thereof level with the top of said container and having a plurality of wells depending from said top portion, an insulating material between the walls of said container and the wells, an air-tight vessel suspended within each of said wells and spaced from the walls thereof, said vessels having flat handles extending outwardly from each side thereof and adapted to rest upon the top portion of the lining, and a cover for said container having a flexible fabric lining secured to the walls of the cover and a packing of insulating material between the top of said cover and said fabric lining, the fabric lining adapted to contact with the flat portion of the lining to the container and hold the flat handles of the air-tight vessels in place.

In testimony whereof I have signed my name to this specification in the presence of two subscribing witnesses.

JAMES ROBERT ADAMS.
